(57) **CLAIM**

The ornamental design for the mobile cooler as shown and
described.

DESCRIPTION

FIG. 1 is an isometric view of a mobile cooler showing my
new design;

FIG. 2 is a right side elevation view thereof;

FIG. 3 is a left side elevation view thereof;

FIG. 4 is a rear elevation view thereof;

FIG. 5 is a front elevation view thereof;

FIG. 6 is a top plan view thereof; and,

FIG. 7 is a bottom plan view thereof.

The broken lines show portions of the mobile cooler that
form no part of the claimed design.

1 Claim, 7 Drawing Sheets
